UNITED STATES PATENT OFFICE.

ROBERT JOHN, OF NEW YORK, N. Y., ASSIGNOR, BY MESNE ASSIGNMENTS, TO ICONO-CHROME COMPANY OF AMERICA, INC., A CORPORATION OF NEW YORK.

DARK-ROOM LANTERN.

1,212,228.

Specification of Letters Patent. Patented Jan. 16, 1917.

Application filed April 26, 1915. Serial No. 24,033.

To all whom it may concern:

Be it known that I, ROBERT JOHN, a citizen of the United States, residing at the city of New York, in the borough of Manhattan and State of New York, have invented certain new and useful Improvements in Dark-Room Lanterns, of which the following is a full, clear, and exact description.

This invention relates to dark-room lanterns which are especially adapted for use in color photography.

The object of the invention is to provide a combination dark-room lantern which gives either a colored light composed of such actinic rays as have slight action upon a color-sensitive photographic plate, whereby the plate may be developed without danger of fogging, or a strong white light when the same is necessary for reëxposing a plate during such processes as require a reversal of the image or the redevelopment of a positive.

Another object of the invention is to provide a combination dark-room lantern of this character, in which the eyes of the operator will at all times be shielded from the glare of the light through the illuminated panes or screens.

The details of the invention will hereinafter appear and the novel features thereof will be pointed out in the claims.

In the accompanying drawings: Figure 1 is a front elevation of a dark-room lantern constructed in accordance with the principles of my invention, and Fig. 2 is a transverse section, taken on the line 2—2 of Fig. 1, and looking in the direction of the arrows.

In the construction shown, the lantern comprises an oblong box or casing 1, preferably made of sheet metal, although wood or any other desired material may be used. This casing has two windows in its front face which are closed by the panes 2 and 3, and through which the rays from a source of white light within the casing are adapted to shine. The pane 2, is preferably of frosted glass or other suitable material which diffuses the white light as it passes therethrough. The same is vertically disposed and is surrounded by a suitable metallic frame 4 by means of which the pane is inset a short distance behind the front wall of the casing, to which the inwardly extending flanges 5 of the frame are secured,

providing a recess or chamber 5'. Hinged at the top of the frame 4, as at 6, is a cover consisting of an outer plate 7 and a pan-shaped plate 8, which has its edges resting against the plate 7 to provide flanges 9. The pan-shaped part 8 of the cover is of a suitable size to fit snugly within the recess 5' formed by the frame 4, so that the cover is light-tight when closed.

The pane 2 is of substantially the same length as the casing 1, but is of slightly less height, leaving a space between the frame 4 and the top wall of the casing 1, which is closed by the pane 3. The pane 3 is also preferably held in a suitable metallic frame 9' and is positioned to the front of the vertical pane 2 and at an angle thereto. The end and top walls of the casing 1 are extended forwardly and are joined to the frame 9', which is so mounted as to make a light-tight joint between it and the top of the frame 4. The rays of white light from the source within the casing are thus prevented from passing to the exterior of the casing except through the pane 3, when the cover 80 for the pane 2 is closed.

It is through the pane 3 that the light passes for illuminating the plate during development. The same is therefore made of a suitably colored translucent material to screen out the rays of light to which the photographic plate is sensitive. For example, if the lantern is designed for use with a well known plate for color photography which is sensitive to the actinic rays of the spectrum having wave lengths less than 650 micro-millimeters, (which rays occur in the red portion of the spectrum), two pieces of glass coated with gelatin and suitably dyed to provide a ray filter which will permit only those rays to pass therethrough which are of a greater wave length than 670 micro-millimeters, are employed. The emulsion on one of the glass plates may be dyed with patent blue, and the other with aurantia. In such case, the light which passes through the pane 3 is red in color.

As is clear from Fig. 2 the pane 3 is disposed at such an angle that the direct rays of light from a source of illuminant centrally disposed within the casing 1 will not pass therethrough. This is done because I find it preferable to use the inner walls of the casing as reflecting surfaces, the reflected light from said walls being directly down- 110

wardly through the pane 3 to illuminate an area below or on a level with the lantern. The developing dish containing the sensitive plate is of course positioned within this area. When the casing 1 is of sheet metal 5 the polished surface thereof acts as a reflecting surface, but when other materials are used, such as wood, the inner walls are made reflecting surfaces by painting them white, or separate reflectors may be used.

10 Since the top wall of the casing 1 extends over the pane 3, that portion of this wall directly above said pane serves as a shield or screen to protect the eyes of the person de-

15 veloping the plate from the glare of light passing through the illuminated pane 3, while at the same time permitting him to clearly see the plate during development since the light is directed upon the limited 20 area in which the plate is positioned. This arrangement has been found to be very satisfactory, as it enables the operator to watch closely the process of development with little strain upon the eyes.

25 When a sheet metal casing is used, it is desirable to provide means for ventilating the same in order to prevent it from becoming unduly heated. An outer casing 13 has been shown which surrounds the casing 1 30 with the exception of its front face; it is joined to the walls of the inner casing 1 by flanges 14. Ventilating openings 15 are provided in one of the end walls of the inner casing 1 through which the heated air may 35 circulate and pass upwardly into the space between the two casings 1 and 13 and into the surrounding atmosphere through openings 16 in the top wall of the outer casing. If desired a ventilating opening 17 may be 40 provided in the bottom wall of the outer casing in order to increase the circulation of air between the walls of the two casings and to prevent the outer casing 1 from becoming unduly heated.

45 Two circular openings of substantially the same size are formed in the walls of the casings 1 and 13 at one end. Secured to and projecting from the casing 13 and surrounding the opening therein is a threaded sleeve 50 18, and located within said openings and extending from the inner casing is a ring 19 which closes the space between the two casings. A threaded cap 20 carrying a lamp socket 21 and switch 22 fits over the threaded sleeve 18. The socket 21 carries an electric incandescent lamp 23 which, when the cap is secured in place, is suitably positioned 55 within the interior of the casing 1.

The cover for the pane 2 is moved to its 60 open position by means of the springs 24 surrounding the pintle 25 of the hinge 6. These springs bear against the side flange 9 of the cover so that when the latter is free to move, they will carry it to the position 65 shown in full lines in Fig. 2, in which posi-

tion the rays emanating from the lamp 23 pass through the pane 2 and flood the developing dish. The inner surface of the plate 8 then acts to reflect the light upon the developing dish, and also serves as a shield or screen to protect the eyes of the person using the lantern from the glare of the light. The cover is maintained in its light-tight closed position by means of a spring catch 26 secured to the bottom wall of the outer casing.

The lantern is preferably supported on short legs 27 which permit the air to enter through the ventilating opening 17.

I claim:

1. A dark room lantern comprising a casing adapted to contain an illuminant having two windows in its front face through which the rays from said illuminant are adapted to pass, a ray filter in the upper of said windows, and an outwardly swinging light-tight cover for the other of said windows pivoted along its upper horizontal edge.

2. A combination dark room lantern comprising a casing adapted to contain an illuminant, said casing having two windows in its front face one of said windows being vertically disposed and having an outwardly swinging light-tight cover therefor, the other of said windows being disposed above said last named window and having a ray filter mounted therein extending forwardly of and at an angle to said first named window.

3. A combination dark room lantern comprising a casing containing an illuminant, said casing having an interior light reflecting surface and two windows in its front face, a ray filter in one of said windows, a movable light-tight cover for the other of said windows, the illuminant and ray filter being so positioned that the transmitted light from the illuminant does not pass through the ray filter but the reflected light passes downwardly through the same.

4. A combination dark room lantern comprising a casing containing an illuminant, said casing having an interior reflecting surface and two windows in its front face, a movable light-tight cover for one of said windows and a ray filter in the other of said windows, the ray filter being disposed above and extending forwardly from, said first named window at an angle thereto, and the illuminant and ray filter being so positioned that the transmitted light from the illuminant does not pass through the ray filter but the reflected light passes downwardly through the same.

5. A combination dark room lantern comprising a casing containing an illuminant, said casing having an interior reflecting surface and two windows in its front face, an outwardly swinging light-tight cover

one of said windows and a ray filter in the other of said windows, the ray filter being disposed above, and extending forwardly from, said first named window at an angle thereto, and the illuminant and ray filter being so positioned that the transmitted light from the illuminant does not pass through the ray filter but the reflected light passes downwardly through the same.

10 6. A combination dark room lantern comprising a casing containing an illuminant, said casing having an interior reflecting surface and two windows in its front face, a movable light-tight cover for one of said 15 windows, a ray filter in the other of said

windows, the ray filter being disposed above, and extending forwardly from, said first named window at an angle thereto, the illuminant and ray filter being so positioned that the transmitted light from the illuminant does not pass through the ray filter but the reflected light passes downwardly through the same, and a shield over said ray filter.

In witness whereof, I subscribe my signature, in the presence of two witnesses.

ROBERT JOHN.
